ABSTRACT OF THE DISCLOSURE

Seamless tubular fabric is formed on a double needlebed machine, such as a Raschel. Two connector guide bars are rendered sufficient by omitting from each bed a needle at each end of each band. Point d'esprit and other lay-in patterns are provided along with a basic hexagonal net.

Production of seamless tubular fabric on a Raschel or similar double needlebed machine is known. Conventional methods for doing so are either unduly restricted in applicability or so complex in character as to be of limited utility.

A primary object of the present invention is to provide a broadly useful and relatively simple method of warp-knitting seamless tubular fabric.

Another object is provision of various designs of seamless tubular warp-knit fabric.

A further object is reduction in apparatus requirements for so knitting such fabric.

Other objects of this invention, together with means and methods for attaining the various objects, will be apparent from the following description and the accompanying diagrams.

FIG. 1 is a double needlebed machine threading diagram utilizable according to the present invention;

FIG. 2 is a point pattern diagram for a "point d'esprit" design of this invention;

FIG. 3 is a point pattern diagram illustrating the interconnection of the front and rear panels of fabric in seamless manner according to the invention;

FIG. 4 is a fragmentary plan of fabric formed according to this invention, showing especially the interconnected edge portions;

FIG. 5 is a legend for FIG. 4;

FIG. 6 is a fragmentary plan of fabric formed according to this invention, showing especially a "point" portion of a "point d'esprit" design and the immediately surrounding portion; and

FIG. 7 is a fragmentary plan of another design embodiment of the invention.

In general, the objects of the present invention are accomplished, in warp-knitting of seamless tubular net fabric on a double needlebed machine, by removing from each bed a needle at each end of each band being knitted and utilizing, in interconnecting the fabric panels being knit on the respective needlebeds, each of two yarn guide bars threaded only at the opposite ends of each band and shogged similarly to the yarn guide bars forming the basic net. Of course, no stitch is formed at the needless positions, and the result is that the pattern being followed in the panels of fabric on the front and back beds is continued at the interconnection between the respective panels along their lateral edges, thereby producing seam-

2

less tubular fabric. More particularly, where the basic net has a reinforced hexagonal design, the respective connector bars alternately form a plurality of stitches (usually three) on the actual end needle in the respective beds and then when shogged to the needless position lay in on the opposite bed for a corresponding plurality of stitches. In effect, the connector bars interchange function, upon being shogged to the needless position, from duplicating the stitching action provided by the basic pattern guide bars to duplicating the laying-in action of the reinforcing guide bars. This action and the result thereof are shown in the diagrams.

FIG. 1 is a threading diagram for a double needlebed machine according to this invention. It includes the threading for a particularly desirable "point d'esprit" design as well as a basic seamless net construction. The diagram is broken away to avoid unnecessary repetition and to emphasize the unique nature thereof at the edge portions of the bands, parts of two bands being indicated. 15 Usually a plurality of individual fabric items are formed alongside but separate (or readily separable) from one another, the lateral extent of each being termed a band, and this invention is adapted to the formation of as many bands as desired commensurate with the size of machine 20 being used, which may be expressed in number of needle positions (per bed). FIG. 1 shows fifty-six needle positions, plus two needless positions, one at each end, per band. The first two needless positions at the right end of the machine (and FIG. 1) are designated **00** and **0**, 25 and subsequent positions are numbered from **1** consecutively to the left, with the designations **00** and **0** added to the regular numbering of positions at which needles have been removed, thus: **57-00** and **58-0**, the former being the last position in the first band and the latter being the first position in the second band.

At the extreme right of FIG. 1 are the designations of yarn guide bars being used, numbered from **1** to **10** (the reference numerals therefor being underlined or italicized to distinguish them from the low-numbered needle numerals). Each bar carries an end of yarn at those positions opposite which a circle or dot is present in this threading diagram. Immediately to the left of the guide bar reference numerals there is an abbreviation indicating the function of the corresponding bars; and to the 40 left thereof is an indication (headed **LINK**) of the initial relative lateral positions of the respective guide bars, the subsequent positions of which are set forth hereinafter in tabular form as pattern chain readings. It will be understood that a zero link positions a guide bar at the closest position to the pattern drum end of the machine (here assumed to be the right end) and that each increase by two in the link designation corresponds to a shogging of each guide in the bar past a single needle position, as is conventional.

55 Thus, bars **4** and **7** are threaded at each needle position except the last, and as designated by **ST** (meaning "stitch") form the basic net, on the front and back needlebeds, respectively. Bars **1** and **10** are threaded at three consecutive positions of every four (i.e., "three in, one out") and are designated **LAY** to indicate that the yarns guided thereby lay in a reinforcement to the basic net, on the front and back beds, respectively. Bars **2** and **8**, which are designated **LO-P** (for "low-point"), are threaded at half the positions at which bars **1** and **10** are not threaded, and bars **60** **3** and **9**, designated **HI-P** (for "high-point"), are threaded 65

at the other half of those positions, each of these four bars being threaded "one in, seven out," with bars 2 and 3 working the front bed and bars 8 and 9 the back bed. The brackets at the extreme right of the diagram indicate that bars 2 and 3 are nested; likewise, so are bars 8 and 9. The starting position for the first threaded guide of the respective bars (also the last threaded guide in the band for bars 5 and 6) is indicated in the following table.

TABLE I

Guide bar:	Starting between Link needles
<u>1</u> -----	0 1 and 2.
<u>2</u> -----	0 0 and 1.
<u>3</u> -----	0 4 and 5.
<u>4</u> -----	2 1 and 2.
<u>5</u> -----	0 00 and 0, 55 and 56.
<u>6</u> -----	2 0 and 1, 56 and 57.
<u>7</u> -----	2 1 and 2.
<u>8</u> -----	0 6 and 7.
<u>9</u> -----	0 2 and 3.
<u>10</u> -----	0 0 and 1.

With FIG. 1 and Table I a person ordinarily skilled in the art of Raschel knitting could thread up a Raschel machine. Normally, also, warping instructions as to the type(s) of yarn and the size and number of spools or beams to be used would also be included, but any convenient yarn, such as 50's stretch nylon, and an ordinary allocation of package number and sizes, would be suitable. Also needed, however, is the pattern to be followed by the various guide bars along the respective needle beds in between the intermittent but continual swinging of the bars as a group to pass their yarn guides between the needle positions of the alternately rising and falling needlebeds. The chain readings for the pattern of an exemplary "point d'esprit" design are set forth in the following table.

TABLE II

	Guide bars

F-----	2/2	4/0	2/2	2/2	2/2	2/2	2/2	4/0	2/2	4/2
B-----	2/2	0/2	2/2	2/2	2/2	2/2	2/2	0/2	2/2	2/2
F-----	4/4	0/4	4/4	4/4	4/4	4/4	4/4	4/4	2/2	2/2
B-----	4/4	2/2	4/4	4/4	4/4	4/4	4/4	2/2	4/0	0/0

Although Table II is only half a dozen courses long (i.e., twelve rows of readings, alternately for the front and back needlebeds) it will be understood that the pattern chains for guide bars 2, 3, 8, and 9 have four times as many links and that the four columns under each bar designation are read vertically in succession.

FIG. 2 shows in conventional point pattern form the stitch construction by representing the path of a yarn guide associated with each of the respective guide bars relative to a single needle position for each. Six courses, designated 1F, 1B, 2F, etc. to 6B, are indicated for all the bars, while courses 16F to 19F and 23F to 24B are also shown for bars 2, 3, 8, and 9. As indicated above, each succession of a half dozen courses for the other bars would be merely a repetition of the first six courses therefor and, thus, need not be shown in the view.

It is apparent from FIG. 2 that guide bars 4 and 7 stitch the basic hexagonal net on the front and back

needlebeds, respectively, and that respective bars 1 and 10 lay in the reinforcement thereof, all in conventional manner. Guide bars 2 and 3 form the so-called "points" in the panel of fabric on the front bed, while bars 8 and 9 form the "points" in the back panel of fabric.

Guide bars 5 and 6 function to interconnect the respective panels of fabric along their opposite edges while preserving the stitch and pattern continuity so as to render the resulting tubular fabric article truly seamless. That they do so is indicated by the next view.

FIG. 3 is a stitch diagram for the stitch and connector bars at several needle positions along the opposite edges of a band, both edges being indicated. The rightmost and leftmost positions are needless and are designated **0** and **00**, respectively. The three intermediate needle positions are designated **1**, **2**, and **3** alongside position **0** and are designated **54**, **55**, and **56** alongside position **00**, it being understood that this view focuses attention on the edges rather than the intermediate portions (between positions **3** and **54**) in the panels of fabric being so formed.

The foregoing views and tables indicate that the threaded guides of connector guide bars 5 and 6, at the opposite ends of the band, effectively flank the threaded guides of stitching guide bars 4 and 7, respectively, and move likewise. Thus, whenever a stitching bar vacates a needle at one end of a bed, the nearby threaded guide of a connector bar moves thereto from the adjacent needless position and stitches on the vacated needle, while at the opposite end of the band, the other threaded guide thereof moves to a needless position and continues its stitching movements there. If there were needles at the needless positions, conventionally two additional connector bars would be employed, each of the four connector bars having only a single guide threaded, two bars being threaded at the left end and two bars at the right end.

FIG. 4 shows fragmentarily the resulting fabric ex-

cluding the "point" portions, one of which is shown separately in a subsequent view. In FIG. 7 the edge portions of the respective panels of the fabric are shown, while the intervening repetitive body portions thereof are omitted in the interest of simplicity of illustration. The heavy broken vertical lines indicate the "seam" location, the front panel being shown therebetween and the rear panel projected outwardly therefrom at both sides for completeness of the showing, it being clearly understood that the fabric could not be so viewed until off the machine and then only by gathering together the omitted portions of the respective panels behind the plane of the view. The yarns from the respective guide bars are coded by shading as indicated in the next view.

FIG. 5 indicates the coding of the yarns in FIG. 4. The solid black yarn is provided by guide bar 1 on the front bed and bar 10 on the back bed. The cross-hatched yarn is provided by guide bar 4 on the front bed and bar

7 on the back bed. The unshaded yarn is provided by guide bar 6, and the stippled yarn by bar 5, on both beds.

Throughout the exemplified construction guide bar 4, which has yarn supplied to one guide thereof per needle in the band, forms the basic hexagonal net on the front needlebed, first forming three stitches on one needle, then three on the next needle to the left, and repeating that cycle. All the while bar 1 lays in the reinforcing yarn, which provides a second end of yarn alongside the single end at the oblique edges (of the hexagons), which result from interchanging of the first yarn from one needle to the next.

Whereas the basic net and reinforcing yarns, respectively, perform their respective roles throughout, it will be apparent from FIGS. 3 and 4 that the yarns provided by the connector guide bars interchange between those two roles after each three courses. Thus, at what otherwise would be the left seam, at the edge represented by the vertical broken line at the left, the yarn from connector guide bar 6 forms three stitches in the front panel like those formed by the yarn from bar 4 and secures yarn laid in from connector guide bar 5 (as a result of attempted stitches thereof at the left needless position in the back bed) like the yarn laid in by bar 1 throughout the panel. Then the yarn from bar 5 forms three stitches in the rear panel, like those formed by bar 7 yarn therein, and the bar 6 yarn is laid therein (corresponding to attempted stitches thereof at the left needless position in the front bed) as the yarn is from bar 10 throughout the panel. Meanwhile at the right "seam" the bar 5 yarn stitches first as the bar 6 yarn lays, and then lays as the bar 6 yarn stitches.

The interchange of roles, on the part of the connector bar yarns, occurs only at the oblique parts of the hexagons, where the two yarn ends run alongside one another. At that location the eye does not recognize, without tracing the yarns through the pattern, which is which. Accordingly, the construction is truly seamless. This is a considerable sales advantage, of course. A corresponding manufacturing advantage lies in the fact that conventional constructions of this type require two additional connector yarn guide bars for seamless construction. Raschel machines with ten guide bars are less costly both to buy and to operate than are those with twelve bars; moreover, at present more ten-bar than twelve-bar machines exist. Of course, the more guide bars a machine has, the more complex patterns of fabric it should be producing.

The "points" of the exemplified fabric require two guide bars working on each needlebed. This is apparent from FIGS. 1 and 2, for example. The terms "high-point" and "low-point" denote the respective resulting locations and structures in each panel of the fabric. At each "point" one of the hexagons is filled in by the yarn laid in from the particular bar. The resulting appearance thereof is shown in FIG. 6.

FIG. 7 shows an alternative laid-in pattern useful in conjunction with the same basic hexagonal net. Contrary to the "point d'esprit" pattern, in which no difference in yarn denier was suggested, this modification employs an obviously much heavier yarn than used in the basic net. Also, the heavy laid-in yarn extends over more than two adjacent wales, thereby lending itself to production of a figured pattern as is itself conventional.

Notwithstanding the foregoing description and accompanying illustration of a preferred embodiment and some degree of modification thereof, other departures may be made, as by adding, combining, or subdividing parts or steps, while maintaining at least some of the advantages of the present invention, which is defined in the following claims.

I claim:

1. Raschel tubular fabric made up from two knitted panels joined seamlessly along their corresponding lateral edges and characterized thereat by continuation of a

balanced basic net configuration formed throughout the panels by stitching yarns and laying-in yarns, each lateral edge junction comprising a pair of yarns knitted differently from the yarns forming the basic net within the panels, the respective yarns in each such pair being knitted identically with the corresponding individual yarns in the other lateral pair, the structure of the fabric along the lateral edges duplicating the net structure present within the panels except for interchange of the respective yarns in each pair between stitching and laying in along successive configurational openings whereas within the panels the stitching yarns stitch throughout and the laying-in yarns lay in throughout the structure.

2. Seamless tubular six-bar Raschel fabric according to claim 1 comprising a balanced net configuration characterized by hexagonal configurational openings.

3. Raschel fabric according to claim 2, wherein occasional configurational openings are opacified by yarns laid-in thereacross.

4. Raschel fabric according to claim 1, characterized by chain readings for guide bars for the basic net yarns as designated under columns 1, 4, 7, and 10 below and by chain readings for guide bars for the interconnecting yarns as designated under columns 5 and 6 below, with 1 and 10 threaded three in, one out and with 1 starting between the first and second needles in the band and with 10 starting between an initial needless position and the first needle in the band, with 4 and 7 threaded at all except the first and last positions in the band and both starting between the first and second needles, and with 5 and 6 threaded only at the first and last positions in the band and with 5 starting between needless positions at the beginning of the band and between the last two needles in the band and with 6 starting between the initial needless position and the first needle in the band and between the last needle and a final needless position in the band:

UNITED STATES PATENT OFFICE
CERTIFICATE OF CORRECTION

Patent No. 3,564,876 Dated February 23, 1971

Inventor(s) Seymour C. Titone

It is certified that error appears in the above-identified patent and that said Letters Patent are hereby corrected as shown below:

Column 1, line 3, "assignor" should read -- assignor --. Columns 3 and 4, Table II, the horizontal underlining of guide bars "2", "3", "8", and "9" should extend over four columns each of chain readings: two to each side thereof. Column 4, line 37, after "fabric" insert a comma. Columns 7 and 8, in the table, the horizontal underlining of guide bars "2", "3", "8", and "9" should extend over 4 columns each of chain readings, as in Table II.

Signed and sealed this 14th day of September 1971.
